UNITED STATES PATENT OFFICE

165,117

FLUID PRESSURE GAUGE OR SIMILAR ARTICLE

Theodore A. St. Clair, South Euclid, Ohio

Application November 4, 1950, Serial No. 12,842

Term of patent 14 years

(Cl. D52—1)

To all whom it may concern:

Be it known that I, Theodore A. St. Clair, a citizen of the United States, residing at South Euclid, Ohio, in the county of Cuyahoga and State of Ohio, have invented a new, original, and ornamental Design for a Fluid Pressure Gauge or Similar Article, of which the following is a specification, reference being made to the accompanying drawing, forming a part hereof.

In the drawings:

Fig. 1 is a side elevational view of a fluid pressure gauge embodying my new design;

Fig. 2 is a front elevational view of the design illustrated in Fig. 1 with the indicator flag visible;

Fig. 3 is a top plan view of the design illustrated in Fig. 1; and

Fig. 4 is a front elevational view of the design

illustrated in Fig. 1 with the indicator flag masked.

The characteristic features of the design reside in the solid line portions.

I claim:

The ornamental design for a fluid pressure gauge or similar article as shown, and described.

THEODORE A. ST. CLAIR.
